CLAIM

The ornamental design for a ratchet type socket
wrench, as shown.

DESCRIPTION

FIG. 1 is a front elevation view of the ratchet type
socket wrench showing the new design;

FIG. 2 is a rear elevational view thereof;

FIG. 3 is a top end view thereof;

FIG. 4 is a bottom end view thereof;

FIG. 5 is a view taken from the left of FIG. 1;

FIG. 6 is a side view taken from the right of FIG. 1;

FIG. 7 is an enlarged detailed view of a portion of the
handle shown in FIG. 6;

FIG. 8 is a section taken on line 8—8 of FIG. 1; and

FIG. 9 is a sectional view taken on section line 9—9 of
FIG. 1.

FIG. 1.

FIG. 2.

FIG. 3.

FIG. 4.

FIG. 5.

FIG. 6

FIG. 8.

FIG. 9.

FIG. 7
